UNITED STATES PATENT OFFICE.

ALLISON L. SCARBORO, OF CHARLOTTE, NORTH CAROLINA, ASSIGNOR TO DRAPER COMPANY, OF HOPEDALE, MASSACHUSETTS, A CORPORATION OF MAINE.

FILLING TENSION DEVICE FOR LOOMS.

SPECIFICATION forming part of Letters Patent No. 794,685, dated July 11, 1905.

Application filed January 21, 1905. Serial No. 242,100.

To all whom it may concern:

Be it known that I, ALLISON L. SCARBORO, a citizen of the United States, and a resident of Charlotte, county of Mecklenburg, State of North Carolina, have invented an Improvement in Filling Tension Devices for Looms, of which the following description, in connection with the accompanying drawings, is a specification, like characters on the drawings representing like parts.

This invention has for its object the production of means to render certain and accurate the operation of the filling detector or fork of a loom when it engages properly-laid filling.

It is usual to provide the lay with a grate or grid to sustain the filling at a number of adjacent points in order that the fork-tines by engaging the filling between such points on the forward detecting beat of the lay shall effect the tilting of the fork. At times this device has been assisted by putting more tension on the filling in the shuttle; but this latter arrangement is objectionable in practice, as the increased tension causes the filling to pull too hard on the selvage when the shuttle is picked. More recently it has been proposed to dispense with the grid and to clamp the filling adjacent the mouth of the shuttle-box when the shuttle is boxed therein on the detecting beat of the lay, leaving the filling entirely without support in front of the filling-detector. In actual practice it has been found that this arrangement is uncertain in operation, apparently because the distance between the selvage and the point at which the filling is clamped is so great that the tension of the filling varies, with consequent variation and uncertainty in the action of the filling-fork, and also because the filling is at times a little slack at the instant it is clamped, causing irregular operation at times.

In my present invention I provide means to sustain the filling at a number of adjacent points in front of the filling-fork, as by a grid, and maintain the filling in position when so sustained by clamping it between the shuttle

when boxed and such sustaining points. I find that by providing such sustaining means for the filling in front of the fork variations in the tension of the clamped filling are completely compensated for, and the fork will always be tilted with absolute certainty when the filling is properly laid, even when there is some slackness in the filling at the instant it is clamped.

The novel features of my invention will be fully described in the subjoined specification, and particularly pointed out in the following claims.

Figure 1 is a partial plan view of a loom at the detecting side and partly broken out with one embodiment of my invention applied thereto. Fig. 2 is a transverse sectional detail thereof on the line 2 2, Fig. 1, looking toward the left; and Fig. 3 is a sectional detail on the line 3 3, Fig. 1, across the guide for the fork-slide, omitting the latter and looking toward the back of the loom.

The lay 1, transversely recessed at 2 opposite the filling detector or fork, the stand or guide 3 for the slide 4, on which at its rear end the filling-fork 5 is pivotally mounted, the shipper S, and weft-hammer W may be and are all of well-known construction and operate in usual manner, the lay being provided at each end with a shuttle-box, the shuttle-box B at the detecting side of the loom being shown in Fig. 1.

At the rear end of the recess 2 I provide means to sustain the filling in front of the fork at a plurality of adjacent points conveniently by a grid g, the bars thereof sustaining the filling, while the tines of the fork 5 engage the filling between its points of support on the detecting beat of the lay.

In order to maintain the filling in proper position when so sustained and to hold it taut without slip at the time the filling-fork operates, I clamp the filling between the shuttle when boxed and the sustaining-points or grid. To this end the foot 6 of the guide 3 is shown as provided with an upright rib 7 parallel to the adjacent side of the

guide (see Figs. 1 and 3) and forming therewith a housing having front and rear ends 8 9, the latter being provided with a deep notch 10, Fig. 3. A cover-plate 11 is adapted to close the top of the housing, said cover-plate being bent down and provided with a lateral flange 12 to rest on the foot 6 and secured thereto by screws 13. An elongated bar, preferably rectangular in cross-section 10 for a portion of its length, as at 14, to slidably fit in the notch 10 and rounded at 15 within the housing, is extended loosely through an opening in the front end 8 of the housing and threaded to receive a nut 16 outside said end. (See Fig. 1.) A collar or other enlargement 17 is secured to the bar within the housing, and between the front end 8 of the latter and said collar a spring s^x 15 is coiled around the part 15 of the slide-bar, 20 the spring tending to retain the bar in the position shown in Figs. 1 and 2. The cover-plate 11, partly broken out in Fig. 1, retains the bar in position within the housing, while permitting longitudinal movement therein, 25 as will be manifest. At its rear end the bar is enlarged and downturned to form a head 18, bifurcated at 19 to receive an upright strip 20 of rubber, leather, felt, or other suitable yielding and non-metallic material 30 and so located that when the lay beats up this clamping member 20 will impinge upon the back wall 21 of the shuttle-box B between its mouth and the grid g prior to the instant at which the detector or fork 5 will 35 engage the filling on the detecting beat.

The filling-detector in the structure herein shown operates on alternate forward beats of the lay, as is common.

When the shuttle S^x is in the box B, the 40 filling t , Fig. 1, when properly laid will extend from the selvage of the cloth to the delivery-eye of the shuttle, and as the lay beats up on the detecting beat the filling will be sustained by the grid g at several adjacent 45 points in front of the fork 5, and the filling will also be caught between the cushion 20 of the head 18 on the slideable member 14 and the back wall of the shuttle-box and clamped. This not only serves normally to hold the filling 50 taut between the clamping-point and the edge of the cloth, preventing it from slipping, but it also maintains it in position to be properly sustained by the grid, so that sufficient resistance is presented to tilt the fork or 55 detector, the spring s^x yielding as the forward movement of the lay moves the slideable member outward toward the front of the loom. The nut 16 acts as a stop to limit rearward movement of the slideable member, and by 60 setting up the nut or letting it off the position of the clamping-head can be adjusted forward or backward.

The grid in a loom ordinarily sustains the filling immediately in front of the detector,

so that the filling will engage and tilt such detector; but if the filling slackens the tines of the detector often push the filling back between the bars of the grid failing to tilt the fork. By means of the clamping device this is absolutely prevented, for the filling is held thereby in proper position across the grid with sufficient tautness to certainly tilt the fork, and no slip of the filling can take place when it is clamped.

Should there be some slight slackness of 75 the filling between the cloth and the clamping-point when clamped or a variation in the tension of this portion of the filling, the sustaining action of the grid compensates therefor and insures the proper fork action.

Thus by the coöperation of the clamping means and the sustaining action of the grid the practical objections arising from the use of either by itself are completely obviated, each acting to complement the operation of 85 the other and compensate for variations in the action thereof, resulting in an always and absolutely reliable yet simple apparatus to effect with perfect certainty the proper action 90 of the filling-detector.

Having fully described my invention, what I claim as new, and desire to secure by Letters Patent, is—

1. In a loom, a lay provided with a shuttle-box, a grid near the mouth of the shuttle-box, a filling-detector movable across the raceway of the lay in front of the grid as the lay beats up, and means to clamp the filling between the grid and the shuttle when the latter is boxed, the grid sustaining the filling in front of the detector while the clamping means maintains the filling taut when engaged by the detector, whereby the action of the latter is rendered certain.

2. In a loom, a lay provided with a shuttle-box, a grid near the mouth of the shuttle-box, a filling-detector to detect presence or absence of the filling in front of the grid when the shuttle is in the shuttle-box, and means supported independently of the lay to clamp the filling between the shuttle and the grid on the detecting beat of the lay, the grid sustaining the filling and insuring certainty in the action of the detector while the clamping means prevents slip of the filling and maintains it properly taut between the shuttle and the cloth.

3. In a loom, a lay provided with a shuttle-box, a grid near the mouth of the shuttle-box, a shuttle, a filling-detector, and yieldingly-mounted means independent of the lay and the shuttle to act upon the filling between the shuttle and the grid and maintain the filling taut across the grid to be engaged by the filling-detector on the detecting beat of the lay.

4. In a loom, a lay provided with a shuttle-box, a grid near the mouth of the shuttle-

box, a shuttle, a filling-detector, and yieldingly-mounted means to coöperate with the back wall of the shuttle-box between the latter and the grid and clamp the filling in position to be sustained by the grid and thereby presented taut to the filling-detector on the detecting beat of the lay.

In testimony whereof I have signed my name to this specification in the presence of two subscribing witnesses.

ALLISON L. SCARBORO.
